United States Patent Office

Des. 185,798
Patented Aug. 4, 1959

185,798

INTERCOMMUNICATIONS UNIT OR SIMILAR ARTICLE

Joseph M. Loge, Los Angeles, Calif.

Application August 8, 1958, Serial No. 52,143

Term of patent 14 years

(Cl. D26—14)

Fig. 1

Fig. 2

Fig. 3

Fig. 4

Figure 1 is a perspective view of an intercommunications unit or similar article, showing my new design;

Figure 2 is a top plan view;

Figure 3 is a side elevational, taken from the right hand side of Figure 2; and

Figure 4 is a rear elevational view.

The dominant features of my design reside in the full line portions of the drawing.

I claim:

The ornamental design for an intercommunications unit or similar article, substantially as shown and described.
